PROCESS OF MECHANICALLY SIMULATING
HANDMADE BRICK

John R. Clark, Battery Park, Md.

Application July 30, 1932, Serial No. 626,817
Renewed April 16, 1935

4 Claims. (Cl. 25—1)

This invention relates in general to ceramics, and more particularly has reference to a method of mechanically simulating handmade brick.

Originally, bricks of the type used in building construction were made by hand. This was accomplished by pouring soft mud into wooden molds. In order to prevent the bricks thus formed from adhering to the walls of the molds, the molds were wetted and sanded prior to the introduction of the soft clay therein. In this manner, after the formation of the bricks in the molds, the same were easily dischargeable therefrom without adhering to the molds.

The bricks made by hand in accordance with this original process were possessed of certain distinctive characteristics now desirable, but at the present time, by reason of the quantity production now essential, it is uneconomical to produce bricks by this method. It has long been sought to produce a machine-made brick having the characteristics of a hand molded brick, but heretofore this has never been accomplished.

A hand molded brick made of soft clay is characterized by folds in the surface thereof, and a sanded finish. This last, the sanded finish, is the most predominant characteristic. The fold appears as the result of relatively soft clay being poured into the mold so as to overlap. As no great pressure was applied in the hand mold process, this pouring of the clay in the molds resulted in the fold appearance on the surface. The sanded appearance, as already stated, was obtained in the hand process by the sand clinging to the wetted walls of the molds, becoming embedded in the surface of the brick in the pouring of the clay therein.

There is a great demand for handmade brick in the present state of architectural trend, by reason of the artistic character of the same. As already pointed out, however, it has heretofore been impossible to produce brick of this character, except by the old and uneconomical method described.

As suggested in the previous description, the desirable sanded appearance of handmade brick is the result of the sand clinging to the walls of the wetted mold becoming embedded in the surface of the brick formed by the pouring of soft clay in the molds. It is due to the fact that the sand in handmade brick is embedded in the surface thereof, that the same adheres thereto so as to present a permanent sanded surface.

As already stated, various efforts have been made to produce a machine-made brick having the surface characteristics of handmade brick, all

of which have uniformly been previously unsuccessful.

Among the expedients which have been attempted has been the wetting of a brick immediately after its formation in a machine, and the application of sand on the wetted surfaces. With the subsequent drying operation in a kiln, however, the sand thus applied has readily brushed off the finished brick so as to negate the effectiveness of such a process. All other prior attempts have likewise proved ineffective. Also, these operations have been carried out on brick produced from machines where the bricks are cut from bars of clay so that from the outset the duplication of the secondary or folded characteristic of handmade brick has recognizably been without possibility of achievement.

Handmade bricks were produced by what is known as a "soft mold" process. Machine-made bricks on the other hand, produced in accordance with the present practices, are made by what has become to be known as a "stiff" or "dry" mud process, that is, in contradistinction to the thin mix employed in the manufacture of handmade bricks, a comparatively dry clay is practically uniformly employed in machine process of producing brick. The stiff dry mud process has come into general use on machines for the reason that a great pressure is made use of, thus allowing a dry mix to be used with the advantage of considerably shortening the subsequent drying and baking of brick in the kiln in view of the considerably lowered moisture content. This is expressed to bring out the fact that by reason of the tremendous pressures employed with the use of a comparatively dry or stiff mix, as is almost universally practiced in the making of brick at this time, and with the cutting of the brick from bars thus produced, it is impossible to obtain the fold effect described as a characteristic of hand brick where soft mud is employed.

Thus, although it may be found that machine-made brick may be sanded so as to simulate handmade brick in this respect, it is entirely impossible to obtain the other character, namely, the feature of folds on the surface of the brick.

An object of this invention is to provide a process for imparting a sanded finish to brick after formation thereof.

Another object of this invention is to provide a process for imparting a sanded finish to machine-made brick.

Still another object of this invention is to provide a process for imparting a folded surface to

machine-made brick, previously characteristic solely of handmade brick.

A further object of this invention is to provide a process of producing machine-made brick having sanded and folded surfaces previously characteristic solely of handmade brick.

With these and other objects in view which may be incident to my improvements, the invention consists in the parts and combinations to 10 be hereinafter set forth and claimed, with the understanding that the several necessary elements comprising my invention may be varied in construction, proportions and arrangement, without departing from the spirit and scope of the 15 appended claims.

In the accompanying drawing,

Figure 1 is a side view, partially in section, of a machine for carrying out my process of making bricks, and

20 Figure 2 is a perspective view of a brick made by such process.

According to the present practice of manufacturing brick, two general processes are employed, both making use of dry or stiff mud. The method 25 most generally followed is the forming of bars of mud under pressure from which individual bricks are cut. The less generally used method is the formation of bricks in individual molds on a wheel by pressing of the mud therein by an adjacent 30 wheel surface.

In the manufacture of bricks by my present invention wherein I produce a machine-made brick having the surface characteristics of a handmade brick, already described in detail, I 35 prefer the use of the latter method of initially forming the brick. In the first process, where the bricks are cut from a bar, it is manifest that all faces are necessarily smooth. It is thus impossible to achieve the desirable folded effect 40 on the surface which I have described, although brick manufactured by this method may have a sanded finish imparted thereto in accordance with the most essential feature of my invention to be hereinafter set forth in detail.

45 In the manufacture of brick, with the use of the wheel apparatus, I find, however, that with certain modifications therein, I am able to produce a brick having the surfaces normally adapted to be exposed after it has been laid, with 50 the desirable fold so as to simulate a handmade brick in this respect.

In the present wheel devices, dies are mounted on one wheel corresponding to the number of molds provided in the other wheel for pressing 55 the mud in the molds to form the brick. An apparatus of this character is unsatisfactory for the reason that there is a progressive change in the center of pressure with the counter-revolution of the wheels, which tends to crack or destroy 60 the mud pressed into each individual mold so as to produce an unsatisfactory brick. If a wheel with merely a flat periphery is substituted for the wheel carrying the dies for operating against the mold wheel, the same disadvantage nevertheless 65 obtains, although to a lesser degree.

I have found that a wheel apparatus will function efficiently, and eliminate this foregoing disadvantage by employing a machine such as is shown in Figure 1, having a pressure wheel 1 70 with a flat periphery 2 spaced from rather than juxtaposed against the mold wheel 3. In a machine of this character, the mud may be fed between the wheels in the usual manner for pressing into the molds, and the excess of mud projecting 75 from each mold, after passing from the pres-

sure wheel, existing by reason of the spacing of the wheels, cut off flush with the top edges of the mold by a knife 5. The excess clay is received in a chute 6, and may be used again. By spacing the wheels in the manner described, the undesirable results accompanying the use of dies on the pressure wheel or the juxtaposition of the wheel against the mold wheel, are not only eliminated but I find that in this manner I am able to produce a brick having the desirable folded 10 surfaces, except the outer surfaces projecting from the mold which is, as I stated, cut off. I find that this folded effect may be markedly obtained on an apparatus of this character by regulating the body of the mix. For the most effective results, although stiff mud is employed, I find it desirable to use a mixture with a slightly higher moisture content than is ordinarily practiced in the usual manufacture of machine-made 15 bricks.

20 In carrying out my invention, I sand the bricks formed by either of the methods described, or any other method, immediately after formation of the same when the moisture content is at the highest, or when the newly formed bricks are most receptive to having sand embedded in the surfaces thereof.

It will be appreciated that it is not expedient to merely sprinkle sand on the brick after the formation of the same, as in a dry or stiff mud 30 process the bricks are not sufficiently moist for the sand to cling thereto. I have also found that even though the bricks may be wetted after the formation of the same, and that even though sand sprinkled thereon will adhere thereto by reason of the moisture of the surfaces, a brick having a sanded surface can nevertheless not be produced for the reason that after the subsequent heat treatment the sand thus applied will drop off.

40 I propose to embed particles of sand in the surface of the brick so as to provide for an actual physical union which will result in a permanent sand finish on the brick. I accomplish this by subjecting the newly formed brick to a sand blast 45 operation. This may be effected by directing nozzles from a suitable sand blast machine at the surface which it is desired to sand. Preferably, the sand blast machine 7 is located above the traveling belt 8 which receives the bricks from the mold wheel. I find that the most effective 50 results may be obtained by spacing the nozzles 9 approximately a foot from the brick surfaces, and at an angle of approximately forty-five degrees with respect thereto; also, the nozzles 55 should be directed at the nearest edge of the brick surface which it is desired to sand. The pressures used in ordinarily building cleaning apparatus with similar machines have been found to be satisfactory, although it may, of course, be 60 found desirable to vary the pressure; also, the invention is, of course, in no wise limited to the specific spacing or directing of the nozzles from the brick.

65 In thus sand blasting the brick, the particles are embedded in the surfaces thereof so that a permanent union is effected, and after the subsequent heat treatment of the brick there is produced a brick with a permanent sand finish having the same sanded appearance as a handmade 70 brick. Such a brick, when finished is illustrated in Figure 2, having the sanded appearance and folds 10, typical of a handmade brick.

75 It is manifest that in carrying out my process, the brick may be produced with only selected

surfaces sanded so that in distinction from hand-made brick having all the surfaces in contact with the mold sanded, in my novel process a brick may be produced having only certain surfaces sanded, if this should be found desirable. Also, it will be apparent that, if deemed desirable, ordinary machine made brick may be manufactured in different colors or varieties of colors on the same brick, produced by blasting the same 5 with different colored sand, or material for imparting any characteristic finish embedded therein, and thus remarkable architectural effects in ordinary bricks achieved, without the use of special clays or the necessity of coloring the clay. 10 It naturally follows that clay of undesirable color may be used in the manufacture of the brick, and the desirable coloring imparted thereto by this process, or coloring materials other than sand, such as pigments, or ground glass, employed in 15 the manufacture of brick or other ceramics, such as tile.

It will be understood from the foregoing that the manufacture of bricks by the wheel method described wherein I find it possible to reproduce 20 the folds on the surface appearing in handmade brick, with the use of my sanding process I am able to practically simulate a handmade brick by machine methods so as to very substantially reduce the costs of such bricks which are now in 25 great demand for architectural purposes. With the use of my sand process, I am able to effectively sand any type of machine made brick so as to impart this primary characteristic of handmade brick thereto. It will also be appreciated 30 that there is produced a more substantial brick than a handmade brick by reason of the pressures under which it is possible to subject a brick in the making in a machine process.

While I have described my preferred method of 35 sanding machine made bricks after the formation of the same by directing a sand blast thereon, it will be apparent that any other method of embedding sand in the surfaces of newly formed brick is clearly within the scope of my invention. 40 Also, it will be clearly understood that my invention is not limited to brick alone, but may be advantageously adapted to other ceramics, for example, tile, in the formation thereof.

There is accomplished by this invention, a

method of simulating a handmade brick respecting the folded and sanded surface characteristics of the same by the machine methods followed in the manufacture of ordinary brick, and a novel sanding process wherein the sanded surface of a 5 handmade brick may be simulated in the manufacture of ordinary brick by any present method; this latter process also being adapted to provide for sanding of selected surfaces of ceramics generally, or for sanding and coloring thereof. 10

While I have shown and described the preferred embodiment of my invention, I wish it to be understood that I do not confine myself to the precise details of construction herein set forth, by way of illustration, as it is apparent that many 15 changes and variations may be made therein, by those skilled in the art, without departing from the spirit of the invention, or exceeding the scope of the appended claims.

I claim:

1. A process of mechanically simulating a handmade brick comprising mechanically molding a brick to present folds in the surfaces thereof like a handmade brick, and embedding sand in the surfaces thus formed to correspond to the 25 sand appearing in the surfaces of a handmade brick.

2. A process of mechanically simulating a handmade brick comprising mechanically shaping a brick to present irregularities in the surface thereof simulating the surface characteristics of a handmade brick, and embedding sand in the surfaces thus formed to correspond to the sand appearing in the surfaces of a handmade 30 brick.

3. A process of mechanically simulating handmade brick comprising mechanically molding a brick to present a fold appearance in the surfaces thereof like a handmade brick.

4. A method of mechanically forming brick to 40 simulate handmade brick, comprising introducing mud into a mold in excess of the capacity of said mold, said mud being of an excess moisture content, rotating the mold and exerting pressure rotatively to the mud, cutting the excess mud 45 flush with the free side of the mold, removing the product from the mold, and embedding sand in the surface of the product.

JOHN R. CLARK.
